UNITED STATES PATENT OFFICE

JOHN M. TOBIAS, OF PITTSBURGH, PENNSYLVANIA.

LIFTING JACK FOR VEHICLES.

1,406,108.

Specification of Letters Patent.

Patented Feb. 7, 1922.

Application filed April 28, 1921. Serial No. 465,205.

To all whom it may concern:

Be it known that I, JOHN M. TOBIAS, residing at Pittsburgh, in the county of Allegheny and State of Pennsylvania, a citizen 5 of the United States, have invented or discovered certain new and useful Improvements in Lifting Jacks for Vehicles, of which improvements the following is a specification.

10 My invention resides in a device for lifting the wheel of an automobile free of the ground as occasion may arise. It is intended primarily for application to and use with automobiles, where it is serviceable when 15 occasion arises to remove or replace a tire. The device, when applied, is brought into play by the travel of the car itself, which ordinarily is effected under the power of the engine, and the advantages attained are 20 simplicity, strength, cheapness, facility of application and removal. There are incidental advantages, over and above the achievement of the primary purpose; these will be mentioned in the sequel.

25 In the accompanying drawings, Fig. I is a view in side elevation of an automobile wheel with the appliance in which my invention resides in place upon it; Fig. II is a fragmentary view, and to larger scale, in 30 vertical section on the medial plane of the wheel; through the wheel and the device of the invention applied; Fig. III is a view of the same fragment of structure shown in Fig. II, but shown in 35 vertical section on a plane at right angles to that of Fig. II, that is to say on a plane perpendicular to the general plane of the wheel; Fig. IV is a view in perspective of that member or element of the device 40 which in the ordinary service of the automobile is removable and replaceable as occasion arises. Fig. V is a view corresponding to Fig. III and illustrating a modification; Fig. VI is a view in elevation of the foot 45 member of the appliance itself, in the modified form of Fig. V, detached from the wheel.

The appliance in which the invention resides is made up of two essential parts, 50 which I shall speak of as anchor member and foot member.

The anchor member is indicated in the drawings by the numeral 1. It is a casting consisting of a block-like body 1, shaped to 55 engage the inner surface of the felly of the wheel and preferably to fill substantially

all of the space between two adjacent spokes. From it extends on one side (it will in service be the side toward the body of the machine) a flange 2, overlying the spokes. 60 This anchor block is recessed, so that when applied an eye a is formed between it and the felly of the wheel. This eye extends transversely and opens across the felly from side to side of the wheel. The anchor block 65 is bolted to the felly of the wheel as is best shown in Fig. II. It will be remarked that as shown in the drawings the bolts by which the anchor block is secured to the felly extend in a direction radial of the wheel. By 70 this arrangement the strains of service are most effectively resisted. The inner surface of the felly, at the point where it is applied, will ordinarily be faced with a metal bearing plate 3, and the body of the block over 75 those surfaces, which (when the block is placed) extend opposite felly and spoke, will advantageously be faced with a layer 4 of leather or other suitable elastic material. Such a filling of elastic material will 80 be effective to hold the block more securely, for it will be perceived (Fig. II) that the space in which this block rests, being defined by the felly and two adjacent spokes, is rounded outwardly, and laterally tapers inward. This anchor block, once applied, is intended to remain in place while the automobile continues in service. It is no impediment at all to normal service, and it affords means by which the foot may be 85 quickly applied and secured, and from which the foot, in turn, may with like facility be removed.

The foot member is conveniently made (this of course is not a limiting point of description) of a forged iron bar, ordinarily a rolled iron bar, conveniently of square cross section shown. This bar is shaped, as is best shown in Fig. IV, into a medial loop 90 and terminal extensions 6. The medial 100 loop is of such shape and size as to be capable of being thrust through the eye a, formed by and between the anchor block 1 and the felly of the wheel. The foot member is otherwise essentially C-shaped, and 105 surrounds the tire on three sides—above and below, and laterally on the side next the car body; it stands free of the tire; and its two terminal extensions 6 overhang the tread of the tire at an interval from the face 110 of the tread. In all these particulars the shape and arrangement of this foot mem-

ber will readily be understood by comparing Fig. IV with the other figures, particularly Figs. II and III. The intermediate portions of the foot member extend opposite the inner side of the wheel, that is the side toward the body of the vehicle, (the right-hand side, as shown in Figure III). The foot member may be provided with a stop conveniently in the form of a pin 7, which in the application of the foot member shall abut against the anchor block 1, to certainly define the proper position of the foot member. The terminal extensions 6 of the foot member may be bridged across by a web 8, the purpose of which is to afford an extended bearing surface for wet ground. From the web 8 extend ground-gripping teeth 9; and these are so disposed that, when the foot member is in service position they extend substantially in the medial plane of the wheel. Conveniently the web 8 is formed of rolled steel, and the teeth 9 are formed from the plate by slitting and pressing, as is sufficiently indicated in the drawings.

The modification shown in Figs. V and VI is characterized by these features: The square-sectional rod of which the foot member is advantageously formed is twisted intermediate the extent of the foot member, and the terminal extensions 6^a accordingly present sharp edges to the roadbed; the web 8^a ceases to be the primary road-engaging member (such office being left to the extensions 6^a) and serves chiefly to prevent sinking in soft ground. With particular regard to Fig. V, it will be seen that in this form there is a line of bearing, extending transversely of the tire of greater length than the diameter of the tire itself.

As has been said, while the car is running in ordinary use, the anchor block 1 will be in place, but the foot member will be stored away in the tool kit, or elsewhere. When, for example, a blow-out has occurred, and a tire is to be removed, the foot member will be applied to the anchor member while the anchor member is at some point in its circle of rotation other than the lowermost. When applied the foot member will take the relative position fully illustrated in Figs. II, III, and V. When the foot member has been so applied, progress of the car in either direction until the appliance comes to the lowermost point in the circle of turning of the wheel will effect the lifting of the car; so that it will rest, not on the tread of the tire, but on the foot member, in the position shown in Figs. I, II, III and V. In this position the tire may be removed and replaced. When all is ready, the further moving of the machine in either direction will shift the machine again to rest upon the tire, while the lifting attachment is carried away from the ground.

When this has happened, the foot member may be removed and put away again.

It will be observed that, when the lifting attachment is in service and the automobile is supported on the foot member, the tire is freely accessible from the outside, that is to say, the left hand side as seen in Fig. III.

I do not intend to give an exhaustive catalogue of incidental advantages, but two or three may be noted. This foot member is adapted to serve, not in place of a lifting jack only, but, when occasion arises, will perform the office of the attachment now familiar by the name "mud hook", to carry the machine out of a mud hole in which the wheel otherwise is slipping. The medial loop 5 of the foot member, projecting through the eye *a*, forms a ring through which the loop of a padlock *b* may be introduced. When the foot member is so locked to the wheel, the automobile is reasonably protected against theft. Figs. I, III, and V show the padlock in place while the foot member is in its car-sustaining position. It will be understood that ordinarily when the lock is in place the foot member is not in this position, but the appliance stands at some other point in the circle of the turning of the wheel. This slightly exceptional showing is resorted to, to save repetition in drawing. The actual state of the case will readily be understood. It will thus be seen that the appliance is at once a lifting member, a mud hook and a theft-preventing appliance.

I claim as my invention:

1. An attachment for a vehicle wheel consisting of an anchor block permanently bolted to the felly of the wheel in a direction radial of the wheel and provided with a seat, and a foot member adapted to be thrust into and removed from the seat in the anchor block, and when in place therein presenting to the road a bearing part overlying and spaced from the tread of the tire, substantially as described.

2. An attachment for a vehicle wheel consisting of a recessed anchor block permanently secured to the felly of the wheel and forming together with the felly an eye extending transversely of and opening across the felly, and a foot member of essentially C shape adapted to be thrust at one end through such eye and when so thrust in surrounding the tire above and below and at one side and presenting to the road a bearing part overlying and spaced from the tread of the tire, substantially as described.

3. An attachment for a vehicle wheel consisting of a looped bar of essentially C shape adapted to be introduced into and removed from a seat formed in the rim of a wheel to receive it and when in place extending opposite and spaced at an interval

- from the tread surface of the tire, substantially as described.
4. An attachment for a vehicle wheel consisting of an eye-like seat opening across the felly of the wheel, and a foot member formed of a looped bar, the medial loop insertible through said eye-like seat and the terminal portions extending when the foot member is in place opposite and spaced at an interval from the tread surface of the tire, with a web provided with road-gripping teeth borne by the terminal portions of the looped bar, substantially as described.
5. An attachment for a vehicle wheel consisting of a looped bar of essentially C shape adapted to be introduced into and removed from a seat formed in the rim of a wheel to receive it, and when in place enclosing the rim above and below and at one side, and standing away from the tire
- at the side and over the tread, the space between the otherwise free ends of the loop being bridged by a web, substantially as described. 25
6. An attachment for a vehicle wheel consisting of a looped bar of essentially C shape adapted to be introduced into and removed from a seat formed in the rim of a wheel to receive it and when in place extending at one end in the form of a padlock-receiving eye adjacent the wheel rim and extending at the other end opposite and spaced at an interval from the tread surface of the wheel, substantially as described. 30 35

In testimony whereof I have hereunto set my hand.

JOHN M. TOBIAS.
